UNITED STATES PATENT OFFICE.

OTTO F. KLOETZER, OF WASHINGTON, INDIANA.

TRAIN-ORDER HOLDER AND HOOK.

Application filed July 10, 1920. Serial No. 395,225.

To all whom it may concern:

Be it known that I, OTTO F. KLOETZER, a citizen of the United States, residing at Washington, in the county of Daviess and 5 State of Indiana, have invented new and useful Improvements in Train-Order Holders and Hooks, of which the following is a specification.

This invention relates to means for facilitating the transmission of a written message from the station master to the engineer, the principal object of the invention being to provide means whereby the engineer can take the order without stopping or checking the 15 speed of the train.

Another object of the invention is to provide means whereby the hooked member on the train can be held in inoperative position and close alongside the part carrying it so 20 as to prevent it from contacting with obstructions along the track.

A further object of the invention is to provide means whereby a hooked member may be detachably connected with a part of 25 the engine or car or caboose so that it can be entirely removed when not being used, said device being made adjustable to fit a pair of uprights forming a part of the car or engine.

30 In describing my invention in detail, reference will be had to the accompanying drawings wherein like characters denote like or corresponding parts throughout the several views, and in which:—

35 Figure 1 is a fragmentary view showing the device attached to a cab of a locomotive.

Figure 2 is a section on line 2—2 of Figure 1.

Figure 3 is a view of a modification.

40 Figure 4 is a sectional view through the right-hand end of Figure 3.

Figure 5 is a view of the message holder which is adapted to be engaged by the hooked member on the train.

45 In Figures 1 and 2, 1 indicates a pair of brackets which are secured in spaced relation to the cab A or other part of a train. A rod 2 has its ends journaled in said brackets and this rod at one end is provided with

50 a hooked member 3 which is of considerable length. A spring strip 4 has one end secured to the rod 2 and its other end engaging the hooked member 3, this strip 4 bridging the space between the rod 2 and member

55 3. This strip 4 is so formed that it will permit an article to pass towards the closed

end of the hooked member but will prevent it from slipping off the hook member after it passes the strip. An arm 5 is secured to rod 2 and passes through a slot 6 formed in 60 the cab. This arm acts as a handle for rocking the rod 2 to move the hook member into the position shown in full lines in Figure 1 or to the position shown in dotted lines in said figure. 65

In the form shown in Figures 3 and 4 the bar 2' has one end rotatably connected with the bracket 1', this bracket being formed of a single piece of material having its ends perforated to receive the reduced portion of 70 the bar 2' and having its outer part bent into U-shape as shown at 7 for engaging an upright bar or other support on a car or engine of the train. A bracket 1^x is provided at the other end of the bar and this 75 bracket is also of U-shape for engaging an upright so that the bar is held between the two uprights. I prefer to connect this bracket to a plunger 8 which has a part 80 slidably mounted in a socket 9 formed in the end of the bar 2', a spring 10 is also arranged in said socket and tends to hold the plunger in its fully extended position. The hooked member and spring on this bar are made similar to those before described. 85 This modified form of hook device can be placed between a pair of uprights on the train and due to the spring plunger arranged at one end of the device it may be placed between bars which are spaced varying 90 distances apart. 90

Figure 5 shows the order holder which consists of the ring 11 and the stem 12 and the spring catch 13 for holding the message or order. 95

The message is placed between the spring and the stem and the device is held with the hand engaging the stem. As the train is passing the engineer swings the hook device upwardly by means of its handle and the station master holds the ring part of the holder in a position where the hook member 3 will pass through the same so that said ring part will be caught by the hook member and held thereon by the spring. The engineer 100 can then drop the handle and permit the device to assume its inoperative position. He can then raise the window of his cab and take the holder and the message from the hook device. 105

110 It will thus be seen that the train need not be stopped or the speed slackened in order to

pass the message to the engineer, thus making a great saving in coal and also lessening the wear and tear on the train due to the stopping and starting of the same.

5 I may provide a small catch 14 for engaging the arm 5 to hold the same in position with the device in inoperative position. This will prevent the swinging of the device due to the movement of the train.

10 What I claim is:—

1. A train order holder comprising a pair of brackets secured in spaced relation to the cab of the train, a rod having its ends journaled in said brackets and a hook member 15 provided at one end thereof, a spring strip having one end secured to said rod and its remaining end engaging the hook members, said strip bridging the space between the rod and the member, an arm being secured 20 to said rod and passing through a slot formed in the cab adapted to act as a handle for rocking said rod to move the hook member into position.

2. A train order holder comprising a pair 25 of brackets secured in spaced relation to the cab of a train, a rod having its ends journaled in said brackets and having a hooked member provided at one end thereof, a

spring strip having one end secured to said rod and its other end engaging the hooked member and said strip bridging space between the rod and member, said strip being so formed that it will permit an article to pass towards the closed end of the hooked member and prevent it from slipping off 30 said member, an arm secured to the rod and passing through a slot formed in the cab, the arm acting as a handle for rocking said rod to move the hooked member to horizontal or inclined position.

3. A device of the class described comprising a pair of spaced brackets, a bar having one end rotatably connected with one of said brackets, the latter being formed of a single piece of material and having its ends 45 perforated to receive the reduced portion of the bar and having its outer part bent into U-shape for engaging a part of the train, a plunger connected to the other bracket and having a part slidably mounted in a socket 50 formed in the end of said bar, a spring arranged in the socket for holding the plunger in extended position.

In testimony whereof I affix my signature.

OTTO F. KLOETZER.
